UNITED STATES PATENT OFFICE

KENNETH S. MCENTIRE, OF KANSAS CITY, MISSOURI

REGULATOR

Application filed October 15, 1927. Serial No. 226,397.

My invention relates to regulators and while it is applicable to various kinds of mechanisms for controlling the latter, in the present instance I have shown it applied to a time-piece for correcting inaccuracies in the running thereof.

When the mechanism constituting my invention is applied to a time-piece as herein-after described, it is adjusted by the minute hand of said time-piece and in turn adjusts the stroke of the pendulum or other speed governing means of said time-piece, to the end that when the latter runs too slow or too fast the stroke of the pendulum or other speed governing means is shortened or lengthened as required to correct the operation of said time-piece.

By the use of my invention guess work and delays in correcting the running of the time-piece are eliminated because if said time-piece should lose or gain, say, ten minutes in twenty-four hours, it is only necessary to advance or retract the minute hand at the end of the initial twenty-four hour period over a space indicating ten minutes on the dial to cause my mechanism to adjust the stroke of the pendulum or other speed governing means to effect the correct running of the time-piece.

In order that the invention may be fully understood, reference will now be had to the accompanying drawing, in which:

Fig. 1 is a broken side elevation of a time-piece equipped with the invention.

Fig. 2 is an enlarged side elevation showing important features of the invention.

Fig. 3 is an enlarged detail of a threaded member and a nut employed in carrying out the invention.

Fig. 4 is a detail of a slotted arm.

Fig. 5 is a detail of an arm provided at one end with a pair of spaced elements.

Fig. 6 is a plan view of a lever.

Referring in detail to the different parts, 2 designates the case, 4 the dial, 6 the pendulum, 8 the pendulum spring, 10 the support for the pendulum spring 8, 12 the verge lever, 14 the minute hand, 16 the hour hand, 18 the shaft upon which the minute hand is fixedly mounted, 20 the tubular shaft upon which

the hour hand is fixedly mounted, 22 a gear wheel which is loosely mounted upon the shaft 18, but normally rotates the latter through the intermediary of a spring or clutch 24 which is fixedly mounted upon said shaft 18 and frictionally engages the adjacent portion of the gear wheel 22, 26 a portion of the time-piece movement which drives the gear wheel 22, and 28 the frame for said movement. All of the foregoing parts may be of ordinary construction.

Referring more particularly to the parts constituting my invention, 30 designates a gear wheel which intermeshes with the gear wheel 22 and is fixedly mounted upon one end of a threaded member 32 which extends transversely through and rotates with the shaft 18, around which latter the gear wheel 30 travels in an orbit.

34 designates a nut arranged to travel in and out upon the threaded member 32, which latter has smooth diametrically reduced portions 40 and 42 at the ends of the thread 36, so that the threads of the nut 34 will not be damaged in the event that the travel of the latter should at any time exceed the length of said thread 36. The outer end of the smooth portion 40 has a cap 44 between which and the outer end of the thread 36 a spring 46 is inserted for forcing the nut 34 back upon said thread 36 in the event that the nut 34 is carried upon the smooth portion 40. Likewise, the smooth portion 42 is provided with a spring 48 for forcing the nut 34 back upon the thread 36 in the event said nut 34 is carried inwardly too far.

The nut 34 is provided with a laterally projecting member 50 which extends through a longitudinal slot 52 in an arm 54 fixed upon the shaft 18 and having one end bent at right angles to engage that end of the threaded member 32 upon which the gear wheel 30 is fixedly mounted. The slotted portion 52 of the arm 54 constitutes a guide for the member 50 and also prevents the latter and the nut 34 from rotating axially with the threaded member 32.

56 designates a pair of spaced elements fixed upon one end of an arm 58. Said elements 56 are spaced apart just far enough to permit the

passage of the member 50 and their ends are curved as indicated at 60 on Fig. 5, so that should said member 50 in its travel around the shaft 18 contact either of said curved ends 5 it will move the arm 58 up or down as the case may be to bring the intervening space 62 into position for the passage of said member 50.

The arm 58 operates in a guide 64 and is connected at its upper end to the slotted end 65 of a lever 66 fulcrumed at 68 and having a bifurcated opposite end 70 through which the pendulum spring 8 extends. In time-pieces where a balance wheel and a hair spring 15 are used instead of a pendulum the lever 66 may be made to vary the effective length of said hair spring so that the speed of the balance wheel will be increased or diminished in the same manner as that of the pendulum.

In the normal operation of the time-piece 20 the gear wheel 22 drives the shaft 18 through the intermediary of the friction spring 24. As the shaft 18 rotates it carries the threaded member 32 therewith and said threaded member 25 32 in turn carries the gear wheel 30 in an orbit around said shaft 18. During this operation the gear wheel 30 is held from axial rotation by the gear wheel 22 and in turn prevents the threaded member 32 from rotating 30 axially. The member 50 in each revolution with the shaft 18 and the nut 34 passes through the space 62 without contacting either of the elements 56 when the time-piece 35 is running accurately. However, should the time-piece lose, say, ten minutes in twenty-four hour, it may be corrected at the end of the initial twenty-four hour period by advancing the minute hand 14 through an arc equivalent to ten minutes upon the dial. This 40 operation causes the shaft 18 to rotate faster than the gear wheel 22 and carry the threaded member 32 and the gear wheel 30 around more rapidly than said gear wheel 22, which latter thereupon causes the gear wheel 30 to rotate 45 axially. Axial rotation of the gear wheel 30 causes the threaded member 32 to rotate axially and move the nut 34 outwardly. As the nut 34 moves outwardly it carries the member 50 therewith which impinges against the 50 lower end of the upper spaced element 56, thereby lifting the same and the arm 58, which latter adjusts the lever 66 so that it will shorten the effective stroke of the pendulum 6 enough to cause the time-piece to 55 keep correct time. On the other hand should the time-piece gain ten minutes in twenty-four hours the minute hand 14 is turned backwardly at the end of the initial twenty-four hour period through an arc indicating ten 60 minutes upon the dial 4, which operation causes the gear wheel 30 and the threaded member 32 to rotate axially in a reverse direction and cause the nut 34 to travel inwardly with the member 50. As the member 50 moves 65 inwardly it contacts with the upper curved

edge of the lower element 56, which in turn lengthens the effective stroke of the pendulum 6 through the intermediary of the arm 58 and the lever 66.

While in the present instance the corrections are assumed to be made in twenty-four hour periods, the pitch of the threaded member 32 or the ratio of the gears 22 and 30 may be proportioned for any desired period of regulation. 70

From the foregoing description it is apparent that I have provided a regulator embodying the advantages above pointed out and while I have shown and described one form of said regulator, I reserve all rights to such changes and modifications thereof as properly fall within the spirit and scope of the invention as claimed. 75

Having thus described my invention, what I claim and desire to secure by Letters Patent, 80 is:

1. The combination with a time-piece having a pendulum, a shaft, a hand fixedly mounted upon said shaft, and a gear wheel forming a part of the movement of the time-piece and adapted through frictional means to normally rotate said shaft in a clockwise direction; a second gear wheel in mesh with the first gear wheel, a threaded member which is actuated by the shaft and carries 90 said second gear wheel in an orbit, and means for adjusting the effective length of the pendulum and which is actuated by said threaded member when the shaft is rotated at higher speed than normal during the setting of 95 the time-piece with the hand. 100

2. The combination with a time-piece having a pendulum, a shaft, a hand fixedly mounted upon said shaft, and a gear wheel forming a part of the movement of the time-piece and adapted through frictional means to normally rotate said shaft in a clockwise direction; of a threaded member extending transversely through said shaft, a gear wheel fixedly mounted upon said threaded member and normally held stationary upon its own axis by the first gear wheel until the hand is manually rotated to the right or left to set the time-piece whereupon the second gear wheel is caused to rotate axially and in turn 115 rotate the threaded member upon which it is mounted, a nut mounted upon and caused to travel inwardly or outwardly upon said threaded member according to the direction in which the latter is axially rotated, and 120 means controlled by said nut and which in turn adjusts the effective length of said pendulum. 115

3. The combination with a time-piece having a pendulum, a shaft, a hand fixedly 125 mounted upon said shaft, and a gear wheel forming a part of the movement of the time-piece and adapted through frictional means to normally rotate said shaft in a clockwise direction; of a threaded member extending 130

transversely through said shaft, a gear wheel fixedly mounted upon said threaded member and normally held stationary upon its own axis by the first gear wheel until the hand is manually rotated to the right or left to set the time-piece whereupon the second gear wheel is caused to rotate axially and in turn rotate the threaded member upon which it is mounted, a nut mounted upon and caused to travel inwardly or outwardly upon said threaded member according to the direction in which the latter is axially rotated, a member projecting from said nut, a pair of connected elements spaced apart for the passage 15 of the last-mentioned member but which are moved in one direction by the latter when it is carried inwardly by the nut and in a reverse direction when said member is carried outwardly by the nut, and intervening members 20 between the spaced elements and the pendulum whereby the effective stroke of the latter is lengthened or shortened according to the direction of movement of said spaced elements.

25 4. In combination with a time-piece having speed governing means, a shaft, and a driven gear wheel having a frictional connection with said shaft for normally driving the latter; a second gear wheel arranged to travel 30 in an orbit about said shaft and normally held from axial rotation by said driven gear, a threaded member extending transversely to and driven by said shaft and caused to rotate axially by said second gear wheel when 35 the shaft is manually rotated in either direction to set the time-piece, a nut mounted to travel upon said threaded member when the latter is rotated axially, and normally stationary mechanism for adjusting the speed 40 governing means and which is controlled by said nut when the latter travels upon the threaded member.

5. In combination with a time-piece having speed governing means, a shaft, and a driven gear wheel having a frictional connection with said shaft for normally driving the latter; a second gear wheel arranged to travel in an orbit about said shaft and normally held from axial rotation by said driven gear, a threaded member extending transversely to and driven by said shaft and caused to rotate axially by said second gear wheel when the shaft is manually rotated in either direction to set the time-piece, a nut 55 mounted to travel upon said threaded member when the latter is rotated axially, spring means at each end of the threaded portion of said member for returning the nut to said threaded portion in the event it runs off the latter, and normally stationary mechanism for adjusting the speed governing means and which is controlled by said nut when the latter travels upon the threaded member.

6. In combination with a time-piece having speed governing means, a shaft, and a

driven gear wheel having a frictional connection with said shaft for normally driving the latter; a second gear wheel arranged to travel in an orbit around said shaft and normally held from axial rotation by said driven gear, a threaded member extending transversely to and driven by said shaft and caused to rotate axially by said second gear wheel when the shaft is manually rotated in either direction to set the time-piece, a nut mounted 70 to travel upon said threaded member when the latter is rotated axially, means for preventing axial rotation of the nut upon said threaded member, and mechanism for adjusting the speed governing means which is moved in one direction by the nut when the latter travels inwardly upon said threaded member and in a reverse direction when said nut travels outwardly.

7. In combination with a time-piece having speed governing means, a shaft, a hand fixed to said shaft, a dial over which said hand is adapted to sweep, and a driven gear wheel having a frictional connection with said shaft for normally driving the latter; a second gear wheel arranged to travel in an orbit about said shaft and normally held from axial rotation by said driven gear wheel, a threaded member extending transversely to and driven by said shaft and caused to rotate axially by said second gear wheel when the hand is manually rotated in either direction to set the time-piece, a nut mounted to travel upon said threaded member when the latter is rotated axially, a normally stationary member which is adjusted by said nut when the latter travels upon the threaded member, and a lever for adjusting the speed governing means and which is controlled by said normally stationary member when the latter is moved by the nut.

8. In combination with a time-piece movement having speed governing means, means in constant gear with said movement and including a threaded member which is rotated axially when the movement is set to correct time, and mechanism for adjusting the speed governing means and which is controlled by said threaded member when the latter is axially rotated.

9. In combination with a time-piece movement having speed governing means, a shaft which may be manually rotated to the right or left to set the time-piece, and a gear mounted upon said shaft to normally drive the latter but free to rotate independently when the shaft is manually rotated; a threaded member journaled in said shaft, a second gear wheel intermeshing with the first gear wheel and mounted upon said threaded member to rotate the latter axially when the shaft is manually rotated, and means for adjusting the speed governing means and which is controlled by said threaded member when the latter is rotated axially.

10. In combination with a time-piece movement having speed governing means, a threaded member which is geared to and rotated axially by said movement when the latter is set to correct time, a nut mounted to travel upon said threaded member, spring means at each end of the threaded portion of said member for returning the nut to said threaded portion should it leave the latter, and mechanism for adjusting the speed governing means and which is actuated by said nut. 75
11. In combination with a time-piece movement having speed governing means and a shaft which latter may be manually rotated to the right or left to set said movement, a lever associated with said speed governing means for adjusting the latter, two spaced elements for controlling said lever, a member arranged to describe orbits of variable diameters in order to pass between said elements or engage and actuate the latter, and means actuated by the time-piece movement for controlling said member. 80
12. In combination with a time-piece movement provided with time-setting and speed controlling mechanisms; mechanism for regulating said speed controlling mechanism and which is permanently connected to and actuated by said time-setting mechanism. 85
13. In combination with a time-piece movement provided with speed controlling and time-setting mechanisms which latter normally is frictionally driven clockwise by said movement but free to turn to the right or left at greater than normal speed when setting the time-piece; a member which is controlled by the time-setting mechanism and in constant gear with the time-piece movement to rotate axially when said time-setting mechanism is adjusted to set the time-piece, and mechanism which is actuated by axial rotation of said member and in turn regulates the speed controlling mechanism of the time-piece. 100
14. In combination with a time-piece movement having speed governing means and a friction driven shaft through which latter said time-piece may be set to correct time, mechanism in constant gear with said movement and provided with means for adjusting the speed governing means each time said shaft is rotated to set the time-piece. 105
15. In combination with a time-piece movement having speed governing means and a friction driven shaft through which latter said time-piece may be set to correct time, a gear wheel in constant mesh with said movement but normally stationary axially, means connecting the gear wheel and the shaft whereby the latter causes said gear wheel to travel in an orbit and cooperates with the movement in causing said gear wheel to also rotate axially when the shaft is rotated at a higher speed than normal to set the time-piece. 115
16. In combination with a time-piece movement having speed governing means, a threaded member which is geared to and rotated axially by said movement when the latter is set to correct time, a nut mounted to travel upon said threaded member, spring means at each end of the threaded portion of said member for returning the nut to said threaded portion should it leave the latter, and mechanism for adjusting the speed governing means and which is actuated by said nut. 120
17. In combination with a time-piece movement having speed governing means, a threaded member which is geared to and rotated axially by said movement when the latter is set to correct time, a nut mounted to travel upon said threaded member, spring means at each end of the threaded portion of said member for returning the nut to said threaded portion should it leave the latter, and mechanism for adjusting the speed governing means and which is actuated by said nut. 125
18. In combination with a time-piece movement having speed governing means, a threaded member which is geared to and rotated axially by said movement when the latter is set to correct time, a nut mounted to travel upon said threaded member, spring means at each end of the threaded portion of said member for returning the nut to said threaded portion should it leave the latter, and mechanism for adjusting the speed governing means and which is actuated by said nut. 130

piece, and means to which the axial rotation of the gear wheel is imparted and which in turn adjusts the speed governing means.

In testimony whereof I affix my signature.

KENNETH S. McENTIRE.
